UNITED STATES PATENT OFFICE.

JOHN DISHLER, OF ADAMS, WISCONSIN.

DESIGN FOR A WINDOW-SHADE BRACKET.

49,796.

Specification for Design.

Patented Oct. 24, 1916.

Application filed September 14, 1916. Serial No. 120,197. Term of patent 3½ years.

To all whom it may concern:

Be it known that I, JOHN DISHLER, a citizen of the United States, residing at Adams, in the county of Adams and State of Wisconsin, have invented a new, original, and ornamental Design for Window-Shade Brackets, of which the following is a specification, reference being had to the accompanying drawing, forming part thereof.

The figure is a perspective view of a window shade bracket, showing my new design.

I claim:

The ornamental design for a window shade bracket, as shown.

JOHN DISHLER.

Witnesses:

JOHN PETERSON,
ROBERT B. WOOD.
